UNITED STATES PATENT OFFICE.

LOUIS G. MILLER AND EDWARD C. LONG, OF WESTMONT BOROUGH, PENNSYLVANIA.

DOOR FOR CARS.

1,280,270.

Specification of Letters Patent.

Patented Oct. 1, 1918.

Original application filed May 4, 1918, Serial No. 232,668. Divided and this application filed July 5, 1918.
Serial No. 243,383.

To all whom it may concern:

Be it known that we, LOUIS G. MILLER and EDWARD C. LONG, both citizens of the United States, and both residing in the 5 borough of Westmont, in the county of Cambria and State of Pennsylvania, have invented certain new and useful Improvements in Doors for Cars; and we do hereby declare the following to be a full, clear, and 10 exact description of the invention, such as will enable others skilled in the art to which it appertains to make and use the same.

Our invention relates to drop doors for 15 railroad freight cars and particularly to those of the hopper or hopper gondola types.

Our invention consists generally in constructing a door adapted to close or open a pair of hoppers, one on either side of the 20 center sill of the car, the necessity for this arising particularly from the fact that the hopper cannot pass through the center sill, as the sill must be continuous throughout the car length and in order to provide the 25 greatest number of openings, most hoppers are arranged in pairs, one on each side of the center sill. Heretofore these doors have been made separately for each hopper and have been connected together by 30 means of what is known as door spreaders of various construction. As opposed to this, we make our door of one piece, one end being adapted to close or open one of the hoppers and the other end adapted to close 35 or open the companion hopper. We preferably make the door narrower at its middle portion just below the center sill, as no closure is required at that place and we therefore save material, besides making the 40 central portion of the door somewhat flexible so that it may twist slightly, if necessary, to insure tight closing against each of the hopper plates. We may also apply a truss structure to the door, adapted to 45 stiffen it, particularly at its narrow portion and where the pull of the operating mechanism is applied, so that it may be drawn up tightly against the hopper without undue deflections, or the stiffening member may be made integral with the door.

This application is a division of our application filed May 4, 1918, Serial No. 232,668, entitled car doors.

Having thus given a general description

of our invention, we will now, in order to 55 make the matter more clear, refer to the accompanying one sheet of drawings in which like characters of reference indicate like parts:

Figure 1 is a top plan view of one style 60 of our improved car door;

Fig. 2 is a transverse sectional elevation taken on the line II—II of Fig. 1;

Fig. 3 is a side edge elevation of the door 65 shown in Fig. 1;

Fig. 4 is a top plan view of a modified style of car door;

Fig. 5 is a transverse sectional elevation taken on the line V—V of Fig. 4;

Fig. 6 is a side edge elevation of the 70 car door shown in Fig. 4;

Fig. 7 is a top plan view of another modified style of car door;

Fig. 8 is a transverse sectional elevation 75 of the door taken on the line VIII—VIII of Fig. 7; and

Fig. 9 is a side edge elevation of the car door illustrated in Fig. 7.

As illustrated in Figs. 1 to 3 inclusive, 80 1 indicates the car door in general, 2 an opening between the two portions thereof, 3 is an integral flange on the forward end of the door which is preferably deeper at its intermediate portions and tapered thence to the ends of the door, this forward flange 85 serving as a stiffening member for the door. This forward flange 3 has an inwardly bent portion 4 adapted to further strengthen and stiffen it. The rear integral flanges of the door are 5 and it is also provided with 90 integral side flanges, as shown, in fact, the entire door is provided with an integral continuous flange extending downwardly from all the edges thereof, the front flange being deeper and tapering as above described. 6 95 is the integral flanged edge of the door at its narrowest portion adjacent to the opening 2, 7 is a pan-shaped brace either formed of pressed plates or a casting secured to the door, as illustrated, and provided with an opening to receive the clevis bolt 8, which is secured thereto, as illustrated, for the purpose of attaching to the door operating mechanism.

Referring now to Figs. 4 to 6 inclusive, 100 9 indicates a slightly modified form of door in general, provided with two end portions and a space or opening 10 between the same,

11 is the front flange portion formed integral with the door, projecting downwardly therefrom and of less depth at the ends than at the central portion, being provided with 5 an integral flanged edge 12 which projects outwardly, as illustrated, to further stiffen the door, in addition to which the reinforcing angle 13 is secured to the intermediate portion thereof, as illustrated. This door 10 is also provided with an integral flange extending around all the edges thereof, that at the narrowest portion being 14 and the rear flange 15. A brace 16, which may be either formed of pressed plates or a casting, 15 is secured to the door, as illustrated, and provided with an opening to receive the clevis bolt 17, which is adapted to be secured to the door operating mechanism.

Referring now to Figs. 7 to 9 inclusive: 20 another slightly modified form of door is indicated generally as 18, 19 is the opening or space between the two portions thereof, the integral rear and end flanges are 20, the integral deeper and tapering front edge is 25 21, provided with forwardly projecting integral portion 22, this door being provided with a pair of flanged stiffeners 23 and 24, the latter being shorter than the former, both secured to the door plate and provided 30 with a space between them at their intermediate portions, adapted to receive the clevis bolt 25, the nut of which rests against the washer plate 26.

It will be seen from the foregoing that we 35 provide a door made in one piece adapted to close a pair of twin hoppers, one on either side of the center sill of the car or otherwise and all margins of the door are provided with downwardly extending flanges 40 formed integrally therewith and the door is also provided with connections to the operating mechanism. These doors are all provided with hinges and hinge plates, the holes for the connections being indicated on the 45 various doors.

Although we have shown and described our improvements in considerable detail, we do not wish to be limited to the exact and specific details shown and described, but 50 may use such substitutions, modifications or equivalents thereof, as are embraced within the scope of our invention, or as pointed out in the claims.

Having thus described our invention, what 55 we claim and desire to secure by Letters Patent is:—

1. A car drop door comprising a metal plate formed integrally with a pair of end portions and a narrower central portion provided with integral marginal edge flanges 60 extending downwardly therefrom, the flange

on the forward longitudinal edge being provided with another integral flange portion.

2. A car drop door comprising a pair of doors integrally united by a narrow portion 65 and provided with an integral downwardly extending marginal flange on all edges thereof, the flange on the forward longitudinal edge being provided with another integral flange portion. 70

3. A car drop door comprising a metal plate formed integrally with a pair of end portions and a narrower central portion provided with integral marginal edge flanges 75 extending downwardly therefrom, the flange on the forward longitudinal edge being deeper and provided with another integral flange portion extending therefrom.

4. A car drop door comprising a metal plate of substantially rectangular outline, 80 the intermediate portion of which is narrower than the end portions, integral downwardly extending marginal flanges on all edges thereof, the flange on the forward longitudinal edge being provided with another 85 integral flange portion, and a stiffening member secured to the narrower portion of the door plate between the flanged edges.

5. A car drop door comprising a metal plate provided with integral marginal edge 90 flanges extending downwardly therefrom, the flange on the forward longitudinal edge being deeper and provided with another integral flange portion extending therefrom, the end portions of same tapering toward 95 the door ends.

6. A car drop door comprising a metal plate narrower at its intermediate portion, integral marginal flanges extending downwardly from all edges thereof, the flange at 100 the forward longitudinal edge being deeper than the others and provided with a further integral flange extending outwardly therefrom, said forward flange tapering gradually from its deeper portion toward the ends 105 of the door.

7. A car drop door comprising a metal plate narrower at its intermediate portion, integral marginal flanges extending downwardly from all edges thereof, the flange 110 at the forward longitudinal edge being deeper than the others and provided with a further integral flange extending outwardly therefrom, said forward flange tapering gradually from its deeper portion toward the ends, and a flanged reinforcing member secured to the door plate near the forward edge thereof. 115

In witness whereof we hereunto affix our signatures:

LOUIS G. MILLER.
EDWARD C. LONG.
